UNITED STATES PATENT OFFICE.

GEORGE HALE BARRUS, OF BROOKLINE, MASSACHUSETTS.

STEAM-BOILER FURNACE.

1,001,336.

Specification of Letters Patent. Patented Aug. 22, 1911.

Application filed December 23, 1909. Serial No. 534,639.

To all whom it may concern:

Be it known that I, GEORGE HALE BARRUS, a citizen of the United States, residing at Brookline, county of Norfolk, State of Massachusetts, have invented a certain new and useful Improvement in Steam-Boiler Furnaces, of which the following is a specification, reference being had therein to the accompanying drawings.

10 My invention has for its object to provide a steam boiler furnace by the employment of which I may secure a more perfect combustion of gaseous coal, as also the prevention of smoke.

15 My invention is more fully set forth in the following description, taken in connection with the accompanying drawings, to which reference is made therein and the novel features thereof are pointed out and 20 clearly defined in the claims at the close of the specification.

Referring to the drawings, Figure 1 is a side elevation partly in section of a well-known form of water tube boiler embodying 25 my invention. Fig. 2 is a section on line 2—2 of Fig. 1, and showing a pair of boilers set side by side. Fig. 3 is a section on line 3—3, Fig. 2. Fig. 4 is an elevation like that shown by Fig. 1, but showing a modified 30 form of draft regulation. Fig. 5 is an elevation like that shown in Fig. 1, and showing still another modification of the draft regulation.

My invention may be employed in connection with boilers of any well known construction.

In Figs. 1 and 2 I have shown a common form of water tube boiler familiar to those skilled in the art and which it will be unnecessary to describe further than to note that the upper row of water tubes is shown at F, and the lower row at G. H is the setting of brick or equivalent material. J are the grate bars, the fire chamber being 45 above them, and the ash pit below them, the door opening through which the furnace is fired is shown at 4, and the ash pit opening at 51. The bridge wall at the rear of the grate is shown at M, and the transverse baffle 50 wall across the space above the boiler tubes at N. The space lengthwise of the water tubes is separated into three portions or passes by the usual baffles shown at O and P.

For the application of my invention two

boilers or the equivalent thereof are necessary. These are indicated at 1 and 2, Fig. 2. They are set side by side, and are separated by a division wall R of any well known construction, which effectually separates each of said boilers from the other. 60 Each furnace is provided with the usual fire door and ash doors located in the boiler front, as also with the proper flue or uptake and a controlling damper or dampers therefor.

65 In Fig. 3 the flue of the boiler, which I have designated 1 (in Fig. 2), is marked B, and the flue of the companion boiler 2 is marked C. The damper in the flue C is indicated at S, and the damper in flue B is 70 designated 5.

In embodying my invention in a pair of boiler furnaces such as above described, the division wall R between the two furnaces is cut away to provide an opening therein 75 indicated at A, the said opening being of a size sufficient to permit the gaseous products of combustion on either grate to pass through the same into the adjoining furnace chamber. While it is not essential that this 80 opening A should be of any particular shape, I prefer to make it of the shape shown in Fig. 1 and to have it located with reference to the grate as there shown, that is, the larger part of the opening being 85 forward of the center of the grate bars and extending downwardly to form an opening A' below the level of the grate bars. Grate bars shown at 8, are placed in said opening on a level with the grate bars J and thus 90 a continuous grate is formed extending across both furnaces in the usual manner and also across the opening A, A' in the division wall. This expedient increases the 95 grate surface to the extent of the thickness of the division wall and contributes to a greater degree of capacity and efficiency in the furnace.

I contemplate that the two furnaces hereinabove referred to shall be alternately fired. 100 If this were done without further provision than as above set forth, the boilers, especially the rear passes thereof, would be alternately subjected to intense heat, and there would consequently be a reduction in the 105 efficiency of the heating surface. To obviate this, I provide a rearward opening in the division wall located between the second or

third passes of the two boilers, and I provide a damper for use in connection with such rear opening which is located between the front pass of each boiler and such rear opening.

I have shown in the drawings three arrangements of this rear opening and its dampers. In Fig. 1, the rear opening in the division wall is shown at W above the second pass of the boiler, and the auxiliary damper V is employed in connection therewith. The damper V, when closed, extends across the space between or directly above the upper row F of tubes and closes the first pass of the boiler. I have shown this damper V as pivoted at its forward end at 9 so that it may be raised or lowered in opening or closing it. This damper may be operated by any well known mechanical means. By closing this damper V in the newly fired furnace and leaving the damper V of the other furnace open, the burning gases from the newly fired coal on the grate below are prevented from passing upwardly through the first pass of the boiler of the newly fired furnace and consequently pass through the opening A, over the incandescent coal on the adjoining grate, upwardly through the first pass of the boiler, the corresponding damper V being open and are then distributed, part of them passing through the opening W and thence through the second and third passes of the boiler which has been newly fired, and part of them passing through the third pass of the other boiler to its discharge flue, the discharge flues of both said boilers being open. In this way, the second and third passes of both said boilers are continually subjected to heat and the loss of heating surface at those points is reduced to a minimum.

In the modification shown in Fig. 4 the opening A extends down to substantially the level of the grates and the rearward opening in the division wall is shown at 14 below the third pass of the boilers. In front of this opening and just rearwardly of the second pass I provide a partition wall 13 which closes the space underneath the boiler tubes in front of the opening 14 and in this partition wall 13 I place a damper 15 whereby the movement of the gas may be controlled. When the damper 15 is closed the burning gases from the companion boiler furnace pass through the opening 14 and thence upwardly through the third pass of the boiler to the flue.

In Fig. 5 still another modification of the rearward opening and damper is shown. In said figure the opening in the division wall is shown at K above the third pass of the boilers and rearwardly of the transverse partition wall N. The coöperating damper is shown at L and overlies and closes the third pass of the boiler; said damper being

pivoted at 10, and being provided with any suitable well known mechanical means for opening and closing it. In this arrangement the damper L of the boiler of the newly fired furnace is closed, and the corresponding damper L of the companion furnace is opened, the products of the newly fired coal pass through the opening A, over the incandescent coals in the companion furnace, rearwardly through the passes of the boiler of this furnace and are then distributed to the passes of both boiler furnaces, part of them passing through the rear opening K.

The operation of a pair of furnaces embodying my invention is as follows: Assuming a bright and level bed of coals of good depth on each grate, the flue dampers of both furnaces being open and the damper in furnace numbered 2 between the rearward opening in the partition wall and the front pass of the boiler being opened, and a charge of coal introduced on the grate of furnace 1. The damper which is thus opened is shown at V, Fig. 1, or if the arrangement shown in Fig. 4 is employed, is shown at 15; or if the arrangement shown in Fig. 5 is employed, is shown at L. The volatile gases given off by the newly fired coal pass horizontally through the opening A in the division wall, over the bed of incandescent coals on the grate of furnace 2. The effect of the heat radiated from these coals upon the gases is to raise their temperature to the ignition point and such of the gases as have not already burned are ignited, and before the cooling surfaces of the boiler tubes are encountered the color of the flame becomes clear white, the smoke disappears and the gas is in a perfect state of combustion. These gases pass rearwardly in furnace numbered 2, through the opening or damper V, or 15, or L, as the case may be, and are then distributed, part of them passing back again through the division wall R by way of the openings W, or 14, or K, respectively. By this distribution of hot gases the rearward pass of both boilers are continuously subjected to a high degree of heat. When the volatile gases are all burned off from the grate of furnace 1, which the fireman can readily determine by observation, the damper V, 15, or L, as the case may be, intermediate the rearward opening in the division wall and the top of the first pass, is opened, and the corresponding damper of the companion furnace 2 closed and a charge of coal is fired upon the grate of furnace 2. The process is now reversed, the gaseous products of combustion from the newly fired coal pass through the opening A in the division wall in the opposite direction over the incandescent coals on the grate of furnace 1. When the gas has all distilled off from the coal on the grate of

furnace 2, the intermediate dampers are again reversed in position, the grate of said furnace being fired and the process repeated.

To insure that the unburned gases which 5 pass through the opening A in the division wall shall be subjected to the full effect of the heat from the incandescent coals in the companion furnace, I apply on top of the lower row of water tubes G, see Fig. 2, a 10 layer 7 of heat resisting material, such as fire-brick tile to cover the spaces between the tubes of each boiler which are nearest the division wall R. The said layer 7 may extend out from said division wall to cover a 15 greater or less number of said tubes. I prefer that the said layer should extend out as shown in Fig. 2 to about one-third or slightly more of the distance across the furnace. The employment of this layer 7 to fill 20 the spaces between the said tubes prevents the gases from rising at once into the tube space and compels them to take a longer course over the incandescent coal and consequently to remain exposed a longer time to 25 the heat from said coal. This expedient insures a more perfect combustion of the gases and reduces to a minimum the gaseous products of combustion which escape from the furnace unburned. The opening A in the 30 division wall R may be extended downwardly to form an opening A' below the level of the grate bars. Grate bars, shown at 8, are placed in this opening on a level with the grate bars in the furnace and thus a 35 continuous grate bar is formed, extending across both furnaces in the usual manner, and also across the opening A' in the division wall. This expedient increases the 40 grate surface to the extent of the thickness of the division wall and contributes to a greater degree of capacity and efficiency in the furnace.

What I claim is:

1. A pair of water tube boilers set side by 45 side, each having its own furnace, a division wall between said two boilers having a front and a rear opening therethrough, transverse partition walls dividing each boiler and its

setting into vertical passes, a damper between each front pass and said rear opening, 50 the said front opening in the longitudinal division wall connecting the two furnaces and the rear opening connecting passes to the rear of the front passes, whereby the said dampers control the path of movement of the 55 products of combustion through the said passes.

2. A pair of boilers set side by side, each having its own furnace, a longitudinal division wall having a front opening and a rear 60 opening, transverse partition walls dividing the space in the setting into passes, the front opening in the longitudinal division wall connecting the two front passes and the rear opening in the longitudinal division wall 65 connecting passes to the rear of the front passes, and a baffle in each of said furnaces above the said front opening and extending outwardly from the said division wall whereby the direction of the unburned gases 70 which pass through said front opening is controlled.

3. A pair of boilers set side by side, each having its own furnace, a longitudinal division wall having a front opening and a rear 75 opening, transverse partition walls dividing the space in the setting into passes, the front opening in the longitudinal division wall connecting the two front passes and the rear opening in the longitudinal division wall 80 connecting passes to the rear of the front passes, and a baffle in each of said furnaces above the said front opening and extending outwardly from the said division wall whereby the direction of the unburned gases 85 which pass through said front opening is controlled, and a continuous grate for both furnaces extending through said front opening in the division wall.

In testimony whereof I affix my signature, 90 in presence of two witnesses.

GEORGE HALE BARRUS.
